UNITED STATES PATENT OFFICE

101,365

DESIGN FOR A COMBINED LAMP PEDESTAL AND HOUSING FOR DISPENSING APPA- RATUS

William M. Hutchison, Indianapolis, Ind., as-
signor to S. F. Bowser & Company, Incor-
porated, Fort Wayne, Ind., a corporation of
Indiana

Application June 6, 1936, Serial No. 63,065

Term of patent 7 years

To all whom it may concern:

Be it known that I, William M. Hutchison, a citizen of the United States, residing at Indianapolis, Marion County, Indiana, have invented a new, original, and ornamental Design for a Combined Lamp Pedestal and Housing for Dispensing Apparatus, of which the following is a specification, reference being had to the accompanying drawing, forming a part thereof.

The single figure is a perspective view of a

combined lamp pedestal and housing for dispensing apparatus embodying my new design. The dominant feature of my design resides in the part illustrated in solid lines.

I claim:

The ornamental design for a combined lamp pedestal and housing for dispensing apparatus, as shown and described.

WILLIAM M. HUTCHISON.
